MINNOW BUCKET

Alfred G. Morreau, Marshall, Tex.

Application November 5, 1946, Serial No. 707,919

2 Claims. (Cl. 43—56)

1

This invention relates generally to minnow buckets, and more particularly to a minnow bucket of simplified form in which the water is kept in a fresh, cool, and aerated condition to the end that live bait can be kept healthy and vigorous for a considerable period of time.

An object of this invention is to provide a minnow bucket in which the coolant compartment and the bait compartment are easily accessible, for the convenient replenishment of coolant and the extraction of bait therefrom.

Another object of this invention is to provide a device of this character in which the water is in constant contact with the outside air and the water is cooled by evaporation as well as by the effect of the coolant.

Another object of this invention is to provide means incorporated with the bucket to conduct fresh cool water from the melting of the coolant, when this coolant is ice, to the bottom of the bucket, further means being provided to void the warm stale water replaced by this fresh water.

A still further object of the invention is to provide a bait bucket which is particularly well adapted for preserving minnows in healthy condition, which is inexpensive and practicable to manufacture, extremely simple and convenient to use, and which is sufficiently sturdy to give durable service.

With these and other objects in view as will appear hereinafter, this invention consists of certain novel features of construction, combination and arrangement of parts as will be herein-after described in detail and particularly set forth in the appended claims, reference being had to the accompanying drawings which form a material part of this application, and in which:

Figure 1 is a top plan view of the bucket with the lids closed.

Figure 2 is a sectional view of the bucket taken on the line 2—2 in Figure 1 and showing the lids partially opened.

Figure 3 is a fragmentary side elevational view showing the detail of the handle and lid fastening means, and the construction of contiguous portions of the bucket.

Similar characters of reference designate similar or identical parts and portions throughout the several views of the drawings.

Referring now to the drawings in detail, this bucket comprises a container preferably of the form of a truncated cone, the tapered sides 10 of which are mortised at the base to receive a bottom 12. A cross member 14 is rigidly secured at both ends thereof to the top of the walls 10,

2

being disposed secantly to this circular top, and unequally sized lids 16 and 18 are hingedly secured to said cross member 14, along flat sides of these lids adapted to abut said cross member. 5 These lids may be reinforced by diametrically disposed straps 22 and 24, which will ordinarily be secured to the lids by screws 25 when this bucket is constructed of wood. In this connection, it may be pointed out that wood or some other porous material is preferred for the construction of this bucket since the water contained therein is cooled by the evaporation of water slowly emitted through the minute pores of such material. The lids may be secured down by hook members 26 engageable in eye members 28 secured on the sides 10 of the bucket, and a pair of handles 30 may be laterally secured to the sides 10 to make the bucket readily portable.

A coolant compartment, generally indicated by 20 the numeral 31, is provided at the top and at one side of the container, the compartment being formed by a horizontally disposed false bottom 32 secured to one side of the container as by the mortising indicated at 34, and a substantially 25 vertical wall portion 36 secured at the top thereof to one edge of the cross bar 14 and secured at the bottom end thereof to the edge of the false bottom 32.

A drain pipe 38, which may be constructed of 30 metal with an annular attachment flange 40 on the upper end thereof, is secured by screws 41 threaded through this flange into the false bottom 32 which is suitably apertured to receive this pipe. The pipe 38 depends in substantially 35 vertical position from the false bottom 32 to within a very short distance of the bottom 12 of the container, and the function of the pipe is to drain the cold water formed from the melting of the ice in the compartment 31, provided ice 40 is used therein, into the lower portion of the container, thus assuring that this fresh water is made available to the live bait confined in the container.

The side walls 10 of the container are apertured as at 42, to provide an overflow outlet for the warm stale water replaced by the fresh water supplied by the melting of the ice. A plurality of apertures 44, preferably arranged in a number of rows horizontally disposed in the portion 45 of the side walls of the container opposite to the compartment 31 and above the level of the overflow outlet 42, are provided to allow aeration of the water in the container when the lid 24 is closed. Obviously, this device must be adapted 50 for easy transportation and any suitable handle 55

means may be secured thereto. In the drawings, there is represented handle means comprising two laterally disposed handles 30, as well as lid fastening means 26 and 28, but any suitable handle means may be provided to co-act with the lids 24 and 26 fastening the same in closed position when the handle means is in operative position. Furthermore, the construction of the compartment 31 may be altered considerably without departure from the scope and spirit of this invention, and it is believed that such modifications fall clearly within the scope of the appended claims.

With the foregoing description of the mechanical details of construction in view, the method of operation of this device will be obvious, but in recapitulation it may be pointed out that ice or another suitable coolant is placed in the compartment 31, preferably being packed tightly therein, and a sufficient amount of water is placed in the container to fill the same up to the overflow 42. Live minnows or other suitable live bait are then placed in the container and the lids 16 and 18 are fastened down by the fastening members 26 and 28. The ice in melting retains the water in the container at a low temperature and the bait is kept in healthy condition. The bucket is adapted to be transported to the fishing grounds and although the lid 16 should be kept closed, the lid 18 may be raised whenever it is required to obtain fresh bait from the container.

Although there has been shown a particular embodiment of this invention, this application is not limited to this particular embodiment, but it is desired to include in the scope of this invention, construction, combination and arrangement of parts and portions substantially as set forth in the appended claims.

Having thus described this invention, what is claimed as new and desired to be secured by Letters Patent is:

1. A bait bucket comprising a container adapted to be partially filled with water, a cross member secured across the top of said container, a coolant compartment laterally disposed within said container and at the top thereof, a drain pipe fixed to and depending from said compartment to a point close to the bottom of said container, and two lids hingedly secured to said cross member covering and allowing access selectively to said compartment and to said water filled portion of said container, the upper portion of the container opposite said compartment having a plurality of small apertures for aerating the water.

5

2. A bait bucket comprising a container adapted to be partially filled with water, a cross member secured across the top of said container, a coolant compartment laterally disposed within said container and at the top thereof, a drain pipe fixed to and depending from said compartment to a point close to the bottom of said container, and two lids hingedly secured to said cross member covering and allowing access selectively to said compartment and to said water filled portion of said container, the upper portion of the container opposite said compartment having a plurality of small apertures for aerating the water.

10

2. A bait bucket comprising a container adapted to be partially filled with water, a cross member secured across the top of said container, a coolant compartment laterally disposed within said container and at the top thereof, a drain pipe fixed to and depending from said compartment to a point close to the bottom of said container, and two lids hingedly secured to said cross member covering and allowing access selectively to said compartment and to said water filled portion of said container, the upper portion of the container opposite said compartment having a plurality of small apertures for aerating the water, said compartment being defined by a partial false bottom in said container and a substantially vertical wall depending from said cross member, which cross member is scantily disposed on the top of said container; said container having a water overflow aperture at a level beneath said false bottom to prevent water from entering said compartment and for directly voiding a volume of stale warm water equal to the volume of fresh cold water formed by the melting of the coolant when said coolant is ice.

ALFRED G. MORREAU.
